UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING-MACHINE.

1,361,104.

Specification of Letters Patent.

Patented Dec. 7, 1920.

Application filed August 5, 1919. Serial No. 315,417.

To all whom it may concern:

Be it known that I, GEORGE A. SEIB, citizen of the United States, and resident of Ilion, in the county of Herkimer and State 5 of New York, have invented certain new and useful Improvements in Typewriting-Machines, of which the following is a specification.

My invention relates to typewriting machines and more particularly to paper feed or controlling devices therefor.

The main object of my invention is to provide a divided or two-part rock-shaft for the paper feeding or controlling devices 15 so connected and supported that when either part or section is turned it will, after a slight lost motion, cause a turning movement also of the other part or section, whereby the paper feeding or controlling devices mounted 20 on said parts or sections may be moved together.

A further object is to provide each shaft part or section with a separate returning spring and to so connect the sections that 25 said springs acting on the paper feeding or controlling devices on the several shaft sections shall have the same or substantially the same pressure on the platen.

A further object of my invention is to 30 provide means of the character specified which may be readily embodied in machines like those now on the market without materially modifying the structural features of such machines as they now exist.

To the above and other ends which will 35 hereinafter appear my invention consists in features of construction, arrangements of parts and combinations of devices set forth in the following description and particu- 40 larly pointed out in the appended claims.

In the accompanying drawings, wherein like reference characters indicate corresponding parts in the various views,

Figure 1 is a fragmentary front elevation 45 of a platen frame and some of the parts carried thereby including the margin feed or control devices of my invention.

Fig. 2 is a transverse sectional view of the same taken on the line $w-w$ of Fig. 1 and 50 looking in the direction of the arrow at said line.

Fig. 3 is an enlarged detail horizontal sectional view of the parts taken on the line $x-x$ of Fig. 1 and looking in the direction 55 of the arrow at said line.

Fig. 4 is an enlarged detail transverse sectional view taken through the rock shaft on the line $y-y$ of Fig. 3 and looking in the direction of the arrow at said line.

Fig. 5 is an enlarged detail transverse sectional view taken through the rock shaft on the line $z-z$ of Fig. 1 and looking in the direction of the arrow at said line.

The present invention may be said to be in the nature of an improvement on the 65 margin feed devices embodied in the Nos. 10 and 11 Remington machines and which are disclosed in the patent to G. H. Smith, No. 1,025,213, dated May 7, 1912.

In such prior devices each margin feed 70 roller was separately released whereas in the present construction an operation of a release key at either end of the platen is effective to simultaneously release both margin feed rollers. In the present instance I have 75 shown my invention embodied in a machine like the No. 10 or No. 11 Remington machine in which the invention may be readily introduced without materially modifying the existing structural features thereof. It 80 should be understood, however, that the invention may be embodied in various styles of typewriting machines.

The platen frame, comprising end plates 1 and a cross bar 2, supports a platen 3 and 85 feed rollers 4 and 5 diagrammatically shown in Fig. 2.

In front of the platen and below the printing line is a divided rock shaft designated as a whole by the reference numeral 6. This 90 shaft extends throughout the length of the platen and intermediate the end plates 1 of the platen frame and comprises two separate and distinct parts or sections. Each section consists of a main body portion 7 which is 95 rectangular in cross section and is provided at its outer end with a cylindrical portion 8, which has a bearing in a sleeve or bushing 9 threaded into a tapped opening in an end plate of the platen frame. The 100 sleeve has a hexagonal or octagonal head 10 adapted for a thin wrench and by which the sleeve may be threaded into and out of the tapped opening. The inner end of each bearing sleeve 9 coacts with a bearing shoulder 8^a on its shaft section to resist an outer thrust of the latter. The outer end of each section of the shaft extends through its bearing sleeve and beyond the head thereof 105 where it has a finger piece, arm or release 110

key 11 fixedly secured thereto as for instance by riveting the arm to the shaft section, as seen at 11^a. As best shown in Fig. 2, a contractile spring 12 is connected at one end 13 to its release key and at the other end to a pin 14 on the associated end plate 1. The power of each spring 12, exerted through its finger piece on a section of the shaft, tends to turn the latter and causes the 10 margin feed roller or device carried thereby to bear against the platen under spring tension or pressure. The inner end portion of each section of the shaft is formed with a cylindrical bearing portion 7^a which is received in a bearing 16 formed at the free end of an arm 17 which constitutes part of a sheet metal bracket 18. This bracket is secured by screws 19 to the cross bar 2 and thus constitutes a support from the platen frame for the inner ends of the sections of the shaft 6. The inner end portion of each shaft section extends beyond its bearing and is slabbed off on one side to form a flat contact face 20 where it overlaps and coacts 25 with the corresponding part on the other section. The two end portions, thus combined to make a lap-joint, present a cylindrical outer surface on the shaft (as shown in Fig. 4) upon which is fairly loosely fitted 30 a sleeve 21 which keeps the flat faces 20 in operative relationship, so that a releasing movement of one section will cause a releasing movement of the other section after a slight lost motion between the two. This 35 lost motion is permitted by the flat faces 20 tending at this time to cam or flex the inner overlapping ends of the shaft sections away from each other until arrested by the loosely surrounding sleeve 21, when the 40 shaft sections can no longer move independently one of the other but must move together, thus causing both paper fingers 23 to move away from the platen. The sleeve 21 is arranged between the bearings 16 and 45 21 is prevented from endwise movement by said bearings.

The rectangular or squared body portion 7 of each section of the shaft is surrounded by a correspondingly shaped sleeve 22 adapted to turn with the shaft but also adapted to be adjusted along the same. Each sleeve 22 is formed integral with its paper finger 23 which extends up from the shaft across the printing line and carries a margin feed roller 24 at its upper end. The power of the springs 12, exerted through the finger piece 11 and the separate section of the shaft, normally presses both margin feed rollers against the platen or the paper thereon. A forward pull or pressure on either finger piece 11 is effective to move both margin feed rollers away from the platen against the power of the springs 12. In order to limit this movement of feed rollers 24 away 60 65 from the platen I provide each finger piece

or arm 11 with a stop or lug 25 which is bent inwardly from the lower end thereof to a point beneath the bottom edge 26 of the associated end plate 1 of the platen frame. The stop 25 coacting with the edge 26 of the plate limits the movements of the parts when either finger piece is moved forward. The springs 12 are balanced so that each margin feed roller may have the same pressure and thus cause the work to be fed straight or evenly at both sides or margins, this being possible by reason of the presence of the lap-joint, which affords a slight lost motion between the sections.

The usual forwardly extending projection or ear 27 is formed on each sleeve 22 for coöperation with stop pins (not shown) to arrest the paper fingers and prevent them from reaching the printing point.

It will be understood of course that the two slabbed off or flat contact portions 20 are loose or unattached to each other but have a bearing one against the other within the loosely surrounding sleeve, so that when one shaft section is turned it will first receive a slight independent movement and then its motion will be transmitted to the other section through the free, overlapping flat contact faces 20. Thus not only does the construction enable both feed rolls to be thrown off by an operation of either shaft section, or its finger piece 11, but it also enables the springs to be self-balancing so as to equalize the pressure of the separate feed rollers 24. If for example the thickness of paper is greater at one feed roller than at the other, the lap joint permits an automatic slight relative movement of the shaft sections and a substantially equal pressure exists at both feed rollers.

By dividing the shaft—or making it in two overlapping but unattached sections—and supporting the inner separated end portions about mid-way of the shaft as a whole, the construction is strong and firm and adapted to any length of carriage and in practice is better than a single, continuous shaft which is more apt to "spring" or sag or be distorted in action in throwing off the margin feed rolls (particularly without a center support) and which besides does not lend itself well to a balancing of the pressures of the margin rolls in a mounting thereof of the kind herein shown.

In assembling the parts each bearing sleeve or bushing 9 is seated on the bearing portion 8 of its shaft section. The section is then introduced endwise through the tapped opening in the end plate in which the associate bushing 9 is to be received and is then passed through the sleeve 22 of the corresponding paper finger and through the bearing 16 for the shaft section and then into the sleeve 21. The bushing is then

threaded into its end plate carrying its shaft section along with it, by reason of the engagement of the latter with the shoulder 8^a, thus moving the inner end of the section 5 farther into the sleeve 21. The other shaft section is introduced into place in a corresponding manner, the inner end of the shaft section being brought into the overlapping arrangement shown when the second section 10 is introduced in place.

What I claim as new and desire to secure by Letters Patent, is:—

1. In a typewriting machine, the combination of a platen frame, a rock shaft comprising two separate sections supported at their outer ends by the platen frame, means for connecting said sections at their inner end portions so as to turn together and permit a slight relative turning movement for 15 a limited extent, margin paper controlling members carried by and adjustable along said rock shaft, and hand controlled means for rocking said shaft.

2. In a typewriting machine, the combination of a platen frame, a rock shaft comprising two separate sections supported at their outer ends by the platen frame, means for connecting said sections at their inner end portions so as to turn together and permit a slight relative turning movement for 20 a limited extent, means carried by the platen frame for supporting each shaft section near its inner end, margin paper controlling members carried by and adjustable 25 along said rock shaft, a spring for turning said shaft, and hand controlled means for rocking said shaft against the power of 30 said spring.

3. In a typewriting machine, the combination of a platen frame, a rock shaft comprising two separate sections supported at their outer ends by the platen frame, a lap-joint formed at the inner end portions of 40 said sections, a sleeve surrounding said lap-joint whereby a slight relative turning movement of the sections may take place before they are caused to turn together, and margin paper controlling members carried 45 by and adjustable along said rock shaft.

4. In a typewriting machine, the combination of a platen frame, a rock shaft comprising two separate sections supported at their outer ends by the platen frame, a lap-joint formed at the inner end portions of 50 said sections, a sleeve surrounding said lap-joint whereby a slight relative turning movement of the sections may take place before they are caused to turn together, means carried by the platen frame for supporting 55 said shaft intermediate the outer ends thereof, and margin paper controlling members carried by and adjustable along said shaft.

5. In a typewriting machine, the com-

bination of a platen frame, a rock shaft comprising two separate sections supported at their outer ends by the platen frame, each section having its main body portion angular in cross-section and its inner end portion cylindrical and slabbed off to form a lap-joint with the corresponding end of the other section, a fairly loosely fitted sleeve surrounding the lap-joint and holding the two co-acting inner end portions of the sections together, whereby a slight relative 65 turning movement of the sections may take place before they are caused to turn together, and a margin paper controlling member carried by and adjustable along the angular portion of each section and connected to turn therewith.

6. In a typewriting machine, the combination of a platen frame, a rock shaft comprising two separate sections supported at their outer ends by the platen frame, each section having its main body portion angular in cross-section and its inner end portion cylindrical and slabbed off to form a lap-joint with the corresponding end of the other section, a sleeve surrounding the lap-joint and holding the two co-acting inner end portions of the sections together, means carried by the platen frame and co-acting 70 with the inner cylindrical end portion of each section to form a bearing and support 75 therefor, a spring for turning said shaft, and a margin paper controlling member carried by and adjustable along the angular portion of each section and connected to turn therewith.

7. In a typewriting machine, the combination of a platen frame, a rock shaft comprising two separate sections supported at their outer ends by the platen frame and having coacting overlapping flat contact 80 faces at the inner end portions thereof, a sleeve which surrounds the inner overlapping end portions of the sections and maintains them connected to turn together, an inner support and bearing for each section intermediate the sleeve and the outer end of the associated section and between which bearings the sleeve is received and held against end-wise displacement, and a margin paper controlling member mounted on and adjustable 85 along each section and adapted to turn therewith.

8. In a typewriting machine, the combination with a platen, of two shaft sections, each supported at its inner end and at its 90 outer end, connecting means whereby when either shaft section is turned it causes a turning movement of the other shaft section, and a paper feeding device on each shaft section.

9. In a typewriting machine, the combination with a platen, of two shaft sections, each supported at its inner end and at its

4
outer end, connecting means whereby when either shaft section is turned it causes a turning movement of the other shaft section, a paper feeding device on each shaft section, and a separate spring for each shaft section.

Signed at Ilion, in the county of Herk-

mer, and State of New York, this 29th day of July, A. D. 1919.
